UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,122,048.

Specification of Letters Patent. Patented Dec. 22, 1914.

Application filed May 18, 1911. Serial No. 628,030.

To all whom it may concern:

Be it known that I, SIDNEY D. WALDON, citizen of the United States, and resident of Detroit, Wayne county, State of Michigan, have invented certain new and useful Improvements in Hydrocarbon-Motors, of which the following is a specification.

This invention relates to hydrocarbon motors and particularly to the oiling system of such motors.

There are two well known oiling systems for lubricating the crank shaft and other bearings of hydrocarbon motors; first, the splash system in which a quantity of oil is placed in the inclosed crank case and the crank shaft and connecting rods splash the oil to the various bearings within the case; and second, the force feed system in which oil is fed under pressure obtained by gravity or by a force pump directly to each of the bearings.

The present invention is shown as embodying a system of the latter type in which the crank case is formed with a drain compartment or sump and the oil which drains into this sump is constantly circulating by a pump through pipe leads to the various motor bearings, and after passing through the bearings is thrown by the rotating parts into the crank case and from there again drains to the sump. Thus a constant circulation of oil is kept up through the motor bearings and since the sump has considerable capacity the system will take care of itself for a reasonable time. In practice, however, it has been found that in a system of this character the oil becomes thin and loses some of its lubricating qualities as it is used over and over again, and heretofore it has been necessary to replenish the supply from time to time in order to keep up the quality of the oil.

One of the objects of the present invention is to automatically keep up the quality of the oil in a circulating system of the kind above referred to, and broadly, therefore, the invention comprises a constant oil circulating system combined with automatic means for constantly supplying fresh oil in measured quantities to the circulating system to keep up the quality of oil therein. It will be understood, of course, that some of the oil in the system is constantly being burned up or otherwise used by reason of

passing around the pistons into the cylinder 55 and by possible leakage, which drain on the system is also taken care of by the fresh oil supply.

Other objects of the invention will appear from the following description and the 60 claims.

In the drawings, Figure 1 is a side elevation and part longitudinal section of a hydrocarbon motor embodying this invention; Fig. 2 is a transverse section through the 65 crank case of the motor shown in Fig. 1; and Fig. 3 is a plan view of the crank case with the motor cylinders removed.

The motor crank case 10 forms the base and support for the motor cylinders 11, 70 shown as cast in pairs and mounted on the crank case in the usual way. The lower half 12 of the crank case is suitably secured to the upper half and it is formed with a sump 13 into which the oil drains through openings 14 after being thrown off from the crank shaft and cam shaft bearings. The crank shaft is shown at 15 and the two cam shafts at 16, these shafts being supported in the crank case and suitably geared 80 together.

In the sump 13 is mounted a circulating pump 17, shown as a gear pump, and the pipe 18 and leads 19 carry the oil under pressure from the pump 17 to the bearings 85 20 of the crank shaft. Suitable leads may also be provided to carry the oil to the cam shaft bearings or the latter may receive their lubrication from the oil thrown from the crank shaft and connecting rods by centrifugal force. Thus it will be seen that there is a constant circulation of lubricating oil from the sump 13, through the pump 17 pipes 18 and 19 and the bearings 20 and then back 90 into the sump through the openings 14.

For supplying fresh oil to the circulating system a tank 21 is mounted on the crank case and a pump 22 draws oil in measured quantities from the tank and forces it through the sight feed 23 directly into the 100 crank case as by the pipe 24. It will, of course, be understood that from the crank case the fresh oil mingle with the other oil therein and flows through the openings 14 into the sump. The tank is provided with 105 a suitable filler cap 23 and sight glass 34.

The pump 17 and the pump 22 may be driven by a single pump operating shaft 25

from one of the cam shafts 16 by spiral gears 26. The lower end of the shaft 25 is directly connected with one of the gears of the pump 17 and the upper end is connected 5 to drive the eccentric 27 of the pump 22 by a pair of spiral gears 28.

In most hydrocarbon motors of the 4 cycle type the crank case is provided with breathers and in the present motor a tube 29 extends 10 from the upper part of the crank case to and through the oil tank 21, for the dual purpose of serving as a breathing pipe and of keeping the oil in the tank warm and in flowing condition. The upper end of the 15 tube 29 is provided with the usual screen 30.

In order that the amount of oil in the sump may be easily determined a float 31 is provided and an indicator stem 32 is attached to the float and extends upwardly 20 through the tube 29 and the screen 30 to a position where it may be observed by the operator.

Having thus described my invention, what I claim is:

- 25 1. In a hydrocarbon motor, the combination with the crank case adapted to contain a quantity of lubricating oil, and means for constantly circulating the crank case oil from and to the crank case, of independent 30 means operated by the motor for supplying fresh oil to the circulating system.
2. In a hydrocarbon motor, the combination with the crank case adapted to contain a quantity of lubricating oil, and means for 35 positively feeding the oil in the crank case to the crank shaft bearings from which it may return to the crank case, of independent means operated by the motor for supplying fresh oil to the crank case.
- 40 3. In a hydrocarbon motor, the combination with the crank case having a sump adapted to contain a quantity of lubricating oil, an oil circulating pump and leads therefrom to the crank shaft bearings for supplying oil to said bearings from the sump, means whereby the oil supplied to said bearings returns to the sump, an auxiliary oil supply tank, and means operated by the

motor for feeding the oil from said tank to the oil circulating system.

4. In a hydrocarbon motor, the combination with the crank case having a sump 50 adapted to contain a quantity of lubricating oil, an oil circulating pump and leads therefrom to the crank shaft bearings for supplying oil to said bearings from the sump, means whereby the oil supplied to said bearings returns to the sump, an auxiliary oil supply tank, and a pump for feeding the oil from said tank to the crank case in 55 measured quantities.

5. In a hydrocarbon motor, the combination with the crank case and motor base, of an oil tank mounted on the motor base, a pump in the crank case for circulating the 65 oil therein, a pump outside the crank case for feeding oil to the circulating system, a shaft for driving both said pumps and means for operating said shaft from the motor crank shaft.

6. In a hydrocarbon motor, the combination with the crank case and motor base, of an oil tank mounted on the motor base, a pump in the crank case for circulating the 75 oil therein, a pump outside the crank case for feeding fresh oil from said tank to the circulating system, a shaft for driving both said pumps, a spiral gear on said shaft, and a spiral gear on the motor cam shaft for driving said pump shaft.

7. In a hydrocarbon motor, the combination with the crank case adapted to contain a quantity of lubricating oil, and an oil supply tank mounted on the crank case, of a breather tube for the crank case passing 85 through said oil tank, a float in the crank case, and an indicating rod on said float passing through said breather tube to a point where it may be observed for indicating the oil level in the crank case.

In testimony whereof I affix my signature in the presence of two witnesses.

SIDNEY D. WALDON.
